PROCESS FOR WASHING SOLVENT LADEN FILAMENTS

BACKGROUND OF THE INVENTION

This invention is concerned with the production of synthetic filaments or yarns and specifically with improved extraction of solvent from dry spun acrylonitrile polymer fibers. Dry spun acrylonitrile polymer filaments as disclosed by Flannagan in U. S. Pat. No. 2,615,198 generally issue from a spinning cell in a solvent-laden condition and in the production of suitable textile yarns it is necessary to reduce the solvent content. One method of solvent extraction involves concurrently washing and drawing the filaments in a cascading water bath as disclosed by Davis and Palmer in U. S. Pat. No. 3,124,631. Prior to such wash-draw processes, it has been customary to combine a large number of yarns coming from individual spinning cells into a composite grouping of yarns usually referred to as a rope and sometimes as a tow. This rope was then deposited in a large storage container called a spinning can. When a large number of full cans had been accumulated, they were placed in a creel arrangement so that the individual ropes were combined into a large tow for solvent extraction, drawing and crimping. It has been found on occasion that this technique of combining warm yarns into a rope, placing the rope in a can with little cooling lead to variations between yarns in their tensile history, variations in temperature history along the rope throughout the can and variations in the amount of solvent eventually extracted. These variations sometimes result in unacceptable final product dyeability and structure variability.

SUMMARY OF THE INVENTION

In the production of rope from dry spun solvent-laden polyacrylonitrile filaments including the steps of combining filaments from a plurality of spinning cells into a composite rope, piddling the rope into a container, forwarding the rope from said container to a liquid bath for washing to extract solvent, and withdrawing wash liquor from the bath, the improved method for extracting solvent from the rope comprising: cooling the withdrawn wash liquor and applying the cooled wash liquor to the rope prior to the washing step. Yarns emanating from the numerous spinning cells of a spinning machine are combined into a rope which is then piddled into containers of special design, each being provided with a foraminous false bottom with the true bottom having a drain or vertical pipe outlet. As the rope is piddled into the can, extraction liquor obtained from a wash-draw machine is cooled and sprayed thereon to cool the rope and extract solvent at this stage. Any surplus liquor which accumulates in the can is withdrawn from the bottom of the can to prevent the liquor level from rising above the false bottom.

BRIEF DESCRIPTION OF THE DRAWINGS

FIG. 1 is a partial schematic flow diagram of the process into which the improved extraction method is incorporated.

FIG. 2 is a perspective elevation of the oscillating piddler spout with attached sprays in association with the false bottom rope container.

DETAILED DESCRIPTION OF THE ILLUSTRATED EMBODIMENT

Referring to FIG. 1, a plurality of spinning cells 10, similar to those described in U. S. Pat. No. 2,615,198, produce a number of solvent-laden yarns 12, which are passed around roller guides 14 and gathered into a composite rope 16 being forwarded by pull rolls 18. The rope is then piddled by means of piddler 20 and associated spout 22 into an open top container 24 where it is held for future processing in combination with similarly prepared ropes. This further processing is carried out in a wash-draw machine part of which is indicated at 30 in the drawing. The operation is similar to that disclosed by Davis and Palmer in U. S. Pat. No. 3,124,631. More particularly, ropes 16 are combined over creel forming rollers 15 into tow 17 which is passed via rolls 19 alternately over and under rolls 31, 32, 33 and 34 in wash-draw machine 30.

20 An outlet valve 35 is placed in the bottom of the first tank at the tow inlet end of wash-draw machine 30 in order to withdraw wash liquor. This liquor is forced by means of a pump 36 through pipe 38 to a cooler or heat exchanger 40. From cooler 40, the liquor is transmitted through pipe 42 and flexible connector 44 to the spray nozzles 46 attached above container 24 on the lower end of spout 22. An additional valve 43 and flowmeter 45 are provided to control flow through spray nozzles 46.

25 30 An outlet pipe 25 is connected from the true bottom 28 of container 24 through valve 23 to pump 27 which exhausts liquor from the bottom of the container out through pipe 29 to a solvent recovery apparatus not shown. Container 24 is provided with a foraminous 35 false bottom 26 located a short distance above the true bottom 28 of the container. Alternatively, the liquor may be withdrawn from the bottom of container 24 through a vertical pipe 25' extending down in one corner of container 24 through false bottom 26 with its open end nearly to true bottom 28 and connected at its other end to pump 27.

35 Referring now to FIG. 2, rope 16 is passed through a pair of rolls 18 into a piddler 20 which may be either a gear piddler or a belt piddler depending on the moisture content of rope 16, e.g., high moisture content would dictate the use of a gear piddler. From piddler 20, rope 16 falls to piddler laydown spout 22 which is supported in a gimbal arrangement as described, for example by Mendes in U. S. Pat. No. 3,378,898. More particularly, a pair of brackets 50 are attached to spout 22 adjacent its upper end and carry opposed stub shafts 52, 54. A mounting fork 56 is pivotally attached to stub shafts 52. A second fork 58 is pivotally attached to stub shafts 54 on brackets 50. The forks 56 and 58 are mounted for reciprocal rotational and reciprocal linear movement, respectively, as indicated by the direction arrows. The spout is thus pivotally mounted to swing simultaneously about intersecting axes to lay the rope 16' in a uniform layered manner in container 24. The container has a foraminous false bottom 26 spaced a distance *d* above the true or closed bottom 28. The distance *d* is generally selected to provide sufficient volume between the false bottom 26 and true bottom 28 to contain the liquid which percolates through the rope after the can has been removed from the filling station, pumped out, and held for further processing steps. During the step, while rope 16 is being laid in can 24 and

liquid sprayed thereon by nozzles 46, the distance d between true and false bottoms provides a reservoir for convenient operation of the liquid withdrawal system. Preferably, four nozzles 46 are mounted to the lower end of spout 22 in such a manner as to uniformly distribute the liquor on rope 16'.

Comparisons were made of a conventional extraction method an apparatus as taught by U. S. Pat. No. 3,124,631 and the extraction method and apparatus of this invention as used in the product of acrylonitrile fiber tow dry spun from a solvent such as dimethyl formamide (DMF) as taught in U. S. Pat. No. 2,615,198. The former extraction method is called "control" and the latter the "test." It was found that the test process required on the average 47.5 percent less wash water per unit weight of tow produced. In addition, it was found that the test tow contained 28.2 percent less residual DMF than the control tow. Finally, the extraction liquor (DMF in water) obtained from the test process contained an average of 80 percent and up to 160 percent more DMF than for the case of the control process.

From this, it is readily apparent that the decreased water consumption, decreased residual solvent content in the end product tow and the increased concentration of extracted solvent in liquor sent to recovery provide

not only monetary savings but also significant improvement in the final product.

What is claimed is:

1. In a process for providing rope from dry spun solvent-laden polyacrylonitrile filaments including the steps of combining filaments from a plurality of spinning cells into a composite rope, piddling the rope into a container, forwarding the rope from said container to a wash-draw machine, washing the rope in a bath of wash liquor in the wash-draw machine, and withdrawing wash liquor from the bath, the improvement comprising: cooling the withdrawn wash liquor in a cooler; applying the cooled wash liquor to the rope while the rope is being piddled into the container; and withdrawing surplus wash liquor from the container.

2. The process as defined in claim 1, said cooled wash liquor being sprayed on the tow as it is being piddled into the container, and then drained from said container.

3. The process as defined in claim 1, wherein ropes from a plurality of containers are combined and forwarded as a composite tow to said wash-draw machine.

4. The process as defined in claim 1, said wash liquor being water and solvent, said solvent being dimethyl formamide.
